UNITED STATES PATENT OFFICE

168,333

SUPPORT FOR A CONTAINER OR THE LIKE

Ernest L. Coble, East Cleveland, Ohio, assignor to The Star Welding & Manufacturing Company, Inc., Cleveland, Ohio, a corporation of Ohio

Application August 16, 1952, Serial No. 21,072

Term of patent 7 years

(Cl. D80—10)

To all whom it may concern:

Be it known that I, Ernest L. Coble, a citizen of the United States, residing at East Cleveland, in the county of Cuyahoga and State of Ohio, have invented a new, original, and ornamental Design for a Support for a Container or the like, of which the following is a specification;

In the drawing,

Fig. 1 is a perspective view of a support for a container or the like showing my new design;

Fig. 2 is a front elevational view; and

Fig. 3 is a side elevational view.

The broken lines shown in Fig. 1 are for illustrative purposes only.

I claim:

The ornamental design for a support for a container or the like, as shown and described.

ERNEST L. COBLE.
